UNITED STATES PATENT OFFICE

WALTHER SCHUCANY, OF DORTMUND, GERMANY

REGENERATIVE GAS-FIRED OPEN-HEARTH FURNACE

Application filed August 24, 1926, Serial No. 131,246, and in Germany September 1, 1925.

This invention relates to improvements in the working of regenerative gas-fired furnaces, more particularly of the open-hearth type, and its object is to create for the furnace a perfectly positive or compulsory combustion process.

With this object in view, according to the present invention,

(1) the gas and combustion air streams issuing from the burners receive an equal, or a predetermined different, heating dependent upon any existing calorific value of the working gas, by an adjustment of the burner outlet flue cross-sections and a consequent distribution of the waste-gas quantities over the regenerative heating chambers,

(2) in connection with the positive supply of the gas and air quantities required for a normal working of the furnace, the ratio of the burner outlet flue cross sections on the fresh gas side end is automatically adjusted corresponding to the existing calorific value of the gas. This adjustment is done in such a way that to the gas and air streams similar energies of movement are imparted whereby with a simultaneous corresponding adjustment of the burner outlet flue axes an intersection of the gas and air streams and thus the whole combustion process takes place on the bath surface only,

(3) the direction or inclination of the burner outlet flue axes is so changed in a continuous alternation that a to-and-fro travel of the point of impact of the flame produced by the intersecting gas and air streams over the whole bath surface is obtained,

(4) said change of the direction or inclination of the burner outlet flue axes can be limited to a certain area or point of the bath surface,

(5) during the to-and-fro travel of the point of impact of the flame on the bath surface, the velocity and direction of the air and gas streams is controlled by varying the cross sections of the air and gas outlet depending upon the distance from the outlet to the point of impact while maintaining

the ratio of the respective gas and air outlets constant,

(6) the reversal of the burners from fresh-gas to waste-gas position, and vice versa, takes place in relative dependence upon one another in such a way that when reversing from fresh-gas to waste-gas position the burner then assuming waste-gas position is at once again prepared for the reversal.

According to the invention, furthermore, an improved arrangement for executing the improved combustion process is provided, by which the following advantages are attained:

(A) Automatic adjustment of the burners to waste-gas and fresh-gas position, to vary the quantities of gas and air flowing therethrough, without the insertion of separate nozzles, in such a way that, on the one hand, on the fresh-gas side the ratio of cross-sections of the burner outlet openings is, according to the calorific value (hereinafter briefly called: value) of the working gas, such that to the gas and air streams, with any value of the gas, energies of movement are imparted which are approximately similar, so that both currents intersect one another on the bath surface and thus the combustion process actually takes place on the bath surface only, while, on the waste-gas side the ratio of cross-sections of the burner openings is regulated depending upon the calorific value of the fuel gas e. g. when gases rich in fuel constituents are used the amount of preheating required for the gas is substantially less than when gases low in fuel constituents are used. When rich gases are used therefore the cross sectional area of the gas outlet is substantially small in comparison to the air outlet, whereas when poor fuel gas is used the cross sectional area of the gas outlet is proportionally larger and approaches or may even attain the cross sectional area of the air outlet.

The sum of the cross-sections of the gas and air channels on the waste-gas side, owing to the larger quantities of waste-gas flowing therethrough and in respect of a

low a passage resistance as possible, is larger than on the fresh-gas side.

(B) Sweeping, in a continuous succession, of each point of the bath surface by the 5 flame produced by the intersecting streams of gas and air.

(C) Perfectly automatic working of the burner arrangement by a positive control of the withdrawal of waste-gas and supply of 10 fresh-gas on each side of the furnace by means of one control shaft.

With the prior burner constructions it was assumed that the heat transmission took place in such a way that the gas and air 15 streams issuing from the burners met on an extension of the axes of the two flues on the bath surface. This could however not be attained with fixed outlet flue cross-sections. With regard to fresh-gas conditions, the outlet 20 cross-section of the gas flue has hitherto been kept small in order to project the gas stream at high speed onto the bath surface, but since on the other hand with regard to the considerably larger waste-gas volume 25 the total cross-section of the gas and air flues of the waste-gas burner must not be reduced beyond a certain minimum, the air flue opening relatively to that of the gas flue must be chosen so large that the burner, 30 for supplying as uniform quantities as possible through both flues per unit of cross-section, that is, per square metre, does not even suffice for working with gas of highest value, for which the air quantity amounts to 35 a multiple of the gas quantity. The air quantity due to its low energy of movement, resulting from the too large outlet flue cross-section, does not reach the bath surface at all but it is upwardly deflected by 40 its buoyancy immediately after its escape from the burner, while the gas current of higher energy of movement does reach the bath surface but is then also upwardly deflected. Gas and air particles come thus in 45 contact with one another and are not ignited on the bath surface, but farther upwards directly beneath the top wall of the furnace. The prior combustion process is thus not at all ideal, because the top wall of the furnace 50 is highly strained by heat whereas the bath itself is rather cooled at the point of impact of the flame by the separately arriving gas stream, and furthermore the whole combustion process takes place but very slowly, so 55 that further combustions occur in the outlet flues.

Thus, the prior burner constructions with fixed outlet flue cross-sections, did not even suit the simplest requirements for the furnace working with a gas of approximately constant value. Said requirements can after all be complied with only by the provision of means for perfectly adapting the energies of movement of the gas and air currents to 60 one another, and in accordance with changes

in the value of the gas necessary during the working of the furnace and requiring a variation in the ratio of quantities of gas and air, and thus of the speeds. Furthermore, with increasing value of the gas also 70 its specific weight is decreased whereby the ratio of cross-sections, of gas to air channel outlet flues, must be further increased for attaining an intersection of the two streams on the bath surface. For attaining said 75 absolutely necessary control of the energies of movement of the gas and air streams, the following conditions must be accomplished:

(1) a positive supply of the gas quantity required for a normal working of the furnace according to the gas value, and of the air quantity required therefor, 80

(2) a control of the ratio of outlet cross-sections of gas and air flues corresponding to the actual quantities supplied and to the specific weight of the gas. 85

An equal, or a predetermined difference as the case may be, heating of gas and air, and furthermore the adaptation of the energies of movement on the fresh-gas side for attaining an intersection of the gas and air currents on the bath surface, can be attained only by, 90

Firstly, fitting the burner heads with outlet flues for gas and air which are adjustable in cross-section, and 95

Then, providing means for allowing an adjustment of the ratio of the flue cross-sections on the fresh-gas and waste-gas side corresponding to the value of the gas. 100

The accompanying drawings illustrate a preferred arrangement for executing the improved process of heating open-hearth furnaces:

Fig. 1 shows that part of the main control spindle which serves for directly acting upon the flap positions; 105

Fig. 12 is a section on the line 12—12 of Fig. 9.

For the purpose of providing the ends of the gas and air flues of the burner heads respectively with adjustable outlets (for the fresh-gas supply) and adjustable inlets (for the waste-gas withdrawal) top and bottom surfaces of the two flues in front of the gas between the burner head and furnace interior are formed as water-cooled (indicated at 11, Fig. 9) turning-flaps 1, 2, 3, 4 (Figs. 1 and 5), the flaps 1 and 2 belonging to the air flue and the flaps 3 and 4 to the gas flue. In order to make a prior combustion by a premature contact between gas and air impossible, between the two middle flaps 2 and 3 a likewise cooled partition-wall 5 (Fig. 5) is provided and firmly connected with the outer casing of the two flues, said wall extending directly to the gap between burner head and furnace interior. The turning of the flaps is effected about hollow shafts 6, through which water is passed and which are rigidly mounted in the outer casing of the furnace, the several operating-rods 7, 8, 9, 10 for the flaps being arranged on the outer ends of said shafts.

The arrangement of the mechanism for actuating the burner flaps as shown in Fig. 4 is for sake of clearness only, the control spindles 14 and 18 (hereinafter explained) being arranged in practice external to the gas and air flues while internal thereto are the water-cooled hollow shafts and burner flaps only.

Fresh-gas side:—

The action upon the respective positions of the burner flaps and thus upon the ratio of the burner outlet flue cross-sections takes place by means of the vertical main control spindle 14 in the following manner: The control of the flaps on the fresh-gas side must be such that, first, the ratio of the outlet cross-sections of the gas and air flues corresponding to the quantities of gas and air flowing therethrough corresponds to a fixed value of the gas, or to the specific weight of the gas, in such a way that with a positive supply of the quantities of gas and air required for said value the energies of movement of the gas and air streams so suit one another that an intersection of both said streams takes place on the bath surface only. Furthermore, for attaining a travel of the point of impact of the flame over the bath surface, on the one hand, the direction of the burner outlet flue axes must be correspondingly displaced and, on the other hand, the outlet openings of the gas and air burners must be narrowed or widened corre-

sponding to the removal or to the approachment of said point of impact from or to the place of issue of the supply, that is, the supplying burners, for adapting the energies of movement of gas and air to the different lengths of the paths taken by the gas and air streams; in which connection, it must be noted, however, that the ratio of outlet cross-sections of the gas and air flues per se, suiting the actual gas value, must always be kept constant.—For a displacement of the burner axes during the travel of the point of impact of the flame on the bath surface, the main control spindle 14, to which the operating-rods 7, 8, 9, 10 are linked, is moved up and down in a continuous alteration by turning to the right or to the left, for which purpose it is mounted with its upper screw-threaded end in a sliding nut 29. The latter is, in cross-head like fashion, clamped in a fixed race member 30, so that it cannot execute any movement during this period.—The adjustment of the actually required flue cross-sections takes place as follows: The free ends of the operating-rods are not directly connected with the main control spindle 14 but located in adjusting nuts 27, 28 by a slot-and-pin connection to suit the changes of length of the rods when turning. Said nuts 27, 28 are screwed upon externally screw-threaded sleeves 15, 15' and 16, 16'. Said sleeves are placed over the main control spindle 14 and provided with an inner guiding groove which is in engagement with a key 124 on the main control spindle 14, whereby the sleeves can be vertically shifted on the main control spindle but are compelled to participate in the rotations of the latter. As hereinafter explained, said sleeves are locked in position on the main control spindle relatively to one another by means of regulating bushes 17, 17' serving for the control in accordance with the actual value of the gas. The directions of the screw-threads of the sliding nut 29 and of the two sleeves 15, 15' (for the air flue) and 16, 16' (for the gas flue) are such that the adjusting nuts 27 (for the air flue) and 28 (for the gas flue) are during one rotary direction of the main control spindle 14 approached to, and during the other removed from, one another, said removal taking place during the downward movement of said approachment during the upward movement of the main control spindle.

Adaptation of the burner outlet openings to the quantities of gas and air flowing therethrough and changing with the gas value:

By the above-described arrangement, the displacement of the point of impact of the flame and the adaptation of the burner outlet openings thereto is effected. Since during the travel of the point of impact of the flame on the bath surface the ratio of outlet

cross-sections of the gas and air flues for the actual gas value must be independent of the change of the outlet openings and thus remain constant, it must be possible to separately act upon the operating-rods for an adjustment of the burner flaps to a fixed gas value. For this purpose, the regulating bushes 17 (air flue) and 17' (gas flue) are provided, of which each engages by screw-threads over each pair of sleeves 15, 15' and 16, 16'. Said regulating bushes are rotatably mounted upon an integral guiding collar 26 of the main control spindle 14, whereby also the sleeves receive their fixed position with reference to the main control spindle 14. Obviously, each pair of sleeves are moved toward or away from one another by correspondingly turning the regulating bushes 17, 17', whereby the flaps of the gas and air flues vary the cross-sections thereof independently from the other action of the main control spindle 14 upon the same. The regulating bushes are driven each by a toothed gearing 57, 107 and 57, 108 respectively from the auxiliary control spindle 18 for the adjustment of the gas value, which spindle is mounted in brackets 24, 25 (Fig. 2).

With reference to the control of the gas value the following must be noted generally: For controlling the whole range from 1100 calories per cubic metre (pure blast-furnace gas) to 4000 calories per cubic metre (coke gas), the ratio of the burner outlet cross-sections of the gas and air flues must be variable from 1:1.1 (pure blast-furnace gas) to 1:4.0 (coke gas). The action upon the flap positions for changing the ratio of cross-sections of the air and gas flues is with the improved arrangement such that always one of said two cross-sections only is changed, the air flue cross-section being variable from a ratio of 1:1.1 (flap position *b*, Fig. 6) to one of 1:1.5 (flap position *a*, Fig. 6) while the gas flue cross-section remains constant during this period (flap position *c*, Fig. 6). From a ratio of cross-sections of 1:1.5 to one of 1:4.0, however, the air flue cross-section remains constant (flap position *b*, Fig. 6) while the gas flue cross-section is gradually narrowed from the position *c* to the position *d*, Fig. 6. In order to permit the regulation bushes for the gas and air flues being driven separately, the two driving toothed wheels 107 (for 17) and 108 (for 17') are loosely mounted on the auxiliary control spindle 18 and can be coupled therewith by means of the two clutches 19 (for 107) and 20 (for 108) respectively, which are positively connected by a double link 21, 21' in such a way that clutch 19 is in engagement when clutch 20 is disengaged, and vice versa. Both clutches are, as long as their links do not exert a pressure thereon,

always held positively in disengaged position by spring action.

The control during the adjustment of a ratio of cross-sections from 1:1.15 to 1:4.0 is as follows: Driving of the auxiliary control spindle 18 is effected from the shaft 34 (Fig. 5) by the bevel gearing 38 (Figs. 2 and 5). The clutch 19 is supposed to be still in engagement from the preceding play. The screw-threads of the regulating bush 17 are so chosen with reference to the rotary direction of the driving shaft 34 that the two sleeves 15, 15' are approached to one another whereby the outlet cross-section of the air flue is gradually widened. The lower end of the sleeve 15' is fitted with an abutment 56. As soon as the ratio of cross-sections has been changed to 1:1.5 (gas outlet to air outlet) by the displacement of the two sleeves with reference to one another, the abutment 56 strikes upon the gear lever 22 fulcrumed at 72, whereby clutch 20 is engaged and the sleeves 16, 16' are removed from one another by the regulating bush 17' and, consequently, the gas outlet cross-section is narrowed (see diagram, Fig. 6). Immediately after the beginning of this movement, the abutment 56 (Fig. 2) of the sleeve 16 frees the lever 23 fulcrumed at 73, whereupon clutch 19 is automatically disengaged.

Coupling of the auxiliary control spindle with the main control spindle:

The driving of the shafts 33, which act upon the main control spindles by means of the bevel gearings 35, and of the shaft 34, which acts upon the auxiliary control spindle 18 by means of the bevel gearing 38, is accomplished by separate and independent control systems operating through a common driving motor 123 (Figs. 4 and 5). The uncoupling of the motor 123 from the shaft 34 and its coupling with the shafts 33, or vice versa, takes place by a corresponding displacement of a hollow shaft 224 mounted on the extended motor shaft 223 and on one end of which one of the two bevel wheels of a bevel gearing 225 for the driving shaft 34 is arranged while on the other end the clutch 226 for driving the toothed gearing 55 (hereinafter mentioned) is located. The reversal of the shaft 34 can be effected by reversing the rotary direction of the motor 123 itself.

The auxiliary control spindle 18 is coupled with the main control spindle only during the adjustment to another gas value, by the toothed gearing 57, 108 or 57, 107 respectively, which coupling takes place automatically in such a way that during the drive of the shaft 34 the ropes 66 are wound-up on a pulley 68 mounted on a friction cone 69 keyed on the shaft 34, whereby, with the aid of links 58 pivoted to pressure-rings 59 (Fig. 2) the toothed wheels 57, which are

loosely mounted on the bushes 17, 17', are pressed with their toothed faces 60 against a likewise toothed projection 61 of the regulating bushes 17, 17' and thereby coupled with the latter. The friction between cone 69 and gearing pulley 68 can be regulated by a corresponding adjustment of the nuts 70 in such a way that, on the one hand, the counter-pressure of the disengaging spring 74 (Figs. 1 and 5) is overcome during the rotation of the driving shaft 34 by pulling the ropes 66 and a corresponding contact pressure between the toothed wheels 57 and the toothed projections 61 of the regulating bushes is produced by the links 58 while, on the other hand, the friction is not so strong that there exists a danger of a breaking of the ropes 66 and of the links, so that the pulley 68 begins to slip on the friction cone 69 at a certain tension of the rope. For indicating the adjusted ratio of the flue cross-sections corresponding to the actual gas value, a runner 71 is arranged on the driving shaft 34 along a scale 71' (Figs. 3, 4 and 5) having characters or numerals thereon indicating the value of the gas corresponding to said ratio.

Thus, as soon as a change in the value of the heating gas takes place, the shaft 34 is put in gear by a displacement of the hollow shaft 224 whereby the toothed gearing 55 is disengaged therefrom. After indication by the runner 71 on the scale 71' of the ratio of cross-sections of the gas and air flues then required, the hollow shaft 224 is again brought into its coupling position with the toothed gearing 55.

Reversal of the furnace working:

Hereinafter, the total working of the arrangement and particularly its reversal to waste-gas or fresh-gas position respectively, is to be described (Figs. 3, 4 and 5). The motor 123 acts, unless with a change of the gas value it is, as mentioned, connected with the common driving shaft 34 of the two auxiliary control spindles 18 by the toothed gearing 55 alternately upon each of the two driving shafts 33 of the main control spindles 14, that is, that controlling the fresh-gas side. In order to change the rotary direction of the main control spindle 14 during the up and down movement of the same without requiring a change of the rotary direction of the driving motor 123, on each driving shaft 33 of the two main control spindles 14 a pair of oppositely disposed beveled gears is mounted, that consists of two loose wheels 84 on the driving shaft 33, which can be coupled therewith by means of the clutches 40, 41 and which are both in gear with the common driving wheel 85 keyed on the intermediary shaft 49, and 50 respectively, between motor-driven toothed gearing 55 and the double bevel-wheel pair. The operation of the clutch actuating rod

43 is effected by a runner 48, or 101 respectively, screwed on the control threads 86 of the driving shaft 33 and prevented from turning thereon, so that it is moved to and fro according to the rotary direction of the driving shaft. 70

The control takes place as follows:

It may be assumed that clutch 41 is engaged and the runner 48 is moving along the control threads 86 from the right to the left, which corresponds to the travel of the point of impact of the flame from the nearest to the farthest (distant) place of impact of the fuel and air on the bath, or respectively to the descent of the main control spindle 14. After completion of the rotations of the driving-shaft 33 required for the extent of said control threads the runner 48 strikes against the fixed abutment 44 of the clutch actuating-rod 43 and reverses the same, by turning it on the two fulcra 87 (Figs. 3 and 4), whereby clutch 41 becomes disengaged and clutch 40 engaged. The rotary direction of the driving-shaft 33 is then also reversed. The runner 48 moves then from the left to the right. The main control spindle 14 ascends, and said point of impact is approaching to the fresh-gas burner. After completion of a certain distance in this direction the runner 48 strikes against the abutment 45, whereby again the reversal to the opposite rotary direction of the driving-shaft 33 is effected. This to-and-fro play is repeated until a reversal of the burner to waste-gas is required. 90

Reversal to waste-gas: For the adjustment of the nozzle flaps 1, 2, 3 and 4 to waste-gas, the abutment 45 is manually turned out of the path of the runner 48, the different parts then move as follows: The main control spindle 14 ascends. The point of impact of the flame travels to the nearest place of impact to the burners, that is the outlet cross-sections at the burner head are widened, and the runner 48 moves along the control threads 86 from the left to the right. The proceeding must then be likewise continued, that is, the runner 48 must further move along the control threads 86 to the right beyond the abutment 45 which for this purpose is turned aside (Fig. 10), until the opening of the nozzle flaps corresponds to the waste-gas position. Then, however, the main control spindle 14 by screwing into the sliding-nut 29 would ascend far beyond the position corresponding to the nearest point of impact, that is the position of the nozzle flaps 1, 2, 3, 4 would have too steep a downward direction when the waste-gas opening is attained. To prevent this, means are provided for permitting, at the reversal to waste-gas and at a certain point of the movement, a further rotation of the main control spindle 14 but preventing a further ascent of the same. For this purpose, the 110 115 120 125 130

sliding-nut 29 is mounted in cross-headlike fashion in the race member 30 (Fig. 3) but so that it can be locked and unlocked therein. As the sliding-nut 29 forms, however, the only supporting bearing for the main control spindle 14, its unlocking from the fixed race member 30 can take place only with the provision of another bearing for the main control spindle. For this purpose, 10 below the screw-threads for the sliding-nut 29 other screw-threads are provided on the upper end of the main control spindle for engagement with the thrust-bearing disc 88. Both said screw-threads run in the same direction, so that, when screwing-up 15 the main control spindle into the sliding-nut, the thrust-bearing disc 88, which is prevented from rotation by clamping-members 89 (Figs. 3 and 8), is screwed down. With 20 an equal pitch of both said screw-threads, there would be no change of the position of height of the thrust-bearing disc 88 with reference to the driving-boss 36, against the upper surface of which it is to bear at the 25 attainment of the intended fixed position of height of the main control spindle after the reversal of the burner to waste-gas in order to serve then as a substitute for the supporting bearing of the main control spindle, 30 previously formed by the sliding-nut 29, which is then unlocked from the race member 30. The pitch of the threads of the thrust-bearing disc must be somewhat higher. As a reversing point to waste-gas 35 position, the place of the nearest point of impact is chosen. The main control spindle is then in its highest position, and the runner 48 has arrived at the place of the then disengaged abutment 45, so that the driving-shaft 38 rotates further in the same direction. The thrust-bearing disc 88 has been 40 screwed toward and at a short distance from a corresponding projection of the driving-boss 36 and it has become disengaged, by a pull on the rope 91 attached thereto the left-hand clamping-contrivance 92 of the sliding-nut 29. The latter would then be further clamped fast by the right-hand clamping-contrivance 93 only, which is however also disengaged by action of the runner 48 upon the lever 94 to which the rope 95 is attached. The two clamping contrivances are mounted each on a caselike projection 104 of the race member 30 (Fig. 7) and their 45 construction is clearly obvious from Figs. 3 and 7.

At the moment when the thrust-bearing disc 88 bears against the driving-boss 36, the clamping members 89 must have freed 50 the disc, so that the same can participate in the rotation of the driving-boss 36 and thus of the main control spindle 14. The clamping of the thrust-bearing disc 88 is effected in such a way that the clamping members are pressed toward one another

by means of blade springs 95' (Fig. 8). The clamping members 89 are located in a recess of the thrust-bearing disc 88. They must thus participate in the up and down movement of the same, but are prevented 70 from turning. Said clamping members are opened for freeing the disc 88 by rotation of the cams 98 mounted on the disengaging shafts 97. Said cams are provided with inner guiding grooves by which they can 75 move up and down along guiding keys provided on the disengaging shafts 97 for the distance of the path of the thrust-bearing disc. The operation of the disengaging shafts is effected by bevel-wheel pairs 99 80 (Fig. 3) from levers 100 arranged in the framing of the race member 30.

The manner in which the levers 100 (Fig. 3) are actuated by the rising and falling of the sliding nut 29 on the spindle 14, is 85 clearly obvious from Fig. 3. Said levers are with locked sliding-nut 29 turned up by the jaws of the latter, while the position of the cams 98 allows a pressing of the clamping members 89 upon the thrust-bearing-disc 88 by means of the springs 95'. After disengagement of the clamping contrivances 92, 93 of the sliding nut 29, the main control spindle is without suspension, since, as aforementioned, also the thrust-bearing disc 88 is still at a short distance from the upper surface of the driving boss 36. For this distance, thus, the main control spindle 14 drops while the jaws of the sliding nut 29 turn the levers 100 downwards, 100 whereby the cams 98 assume such a position that the clamping members free the thrust-bearing disc 88. The latter bears then against the projection of the driving-boss 36. A further screwing of the same 105 on the main control spindle is prevented by friction of the contact faces which is further increased by the preferable toothed weight of the main control spindle then suspended from the thrust-bearing disc. The main 110 control spindle maintains thus its actual position of height, while with continued rotation in the same direction a further screwing-asunder of the nozzle flaps 1, 2, 3, 4 takes place by an approachment of the 115 nozzle adjusting nuts on the pertinent sleeves 15, 15', 16, 16' until the required waste-gas opening is attained. The sliding-nut 29 has meanwhile been screwed down for a corresponding distance on the main 120 control spindle, while the runner 48 has further moved in the hitherto direction to the right on the control threads of the driving-shaft 33. Shortly before the attainment of its position on the control threads 125 86 corresponding to the waste-gas position of the nozzle flaps 1, 2, 3, 4 the runner 48 embraces with its lower arm the double-armed lever 53, the other arm of which acts upon the clutch rod of the main motor 130

clutch 51 in such a way that the right-hand burner side is put to work. In this connection, it must be noted that the motor clutches are by spring pressure continuously held in disengaged position, unless they are acted upon by the lever 53 for clutch 51 and 53' for clutch 52. The two gearing levers 53, 53' are mounted on a common shaft 54 forming the fulcrum for the same. Then for a short moment, the mechanism for both furnace sides is at work, the runner 101 of the right-hand side moving to the right and freeing the lever 53', so that motor clutch 52 is disengaged by its spring pressure. The runner 48 is then in a position corresponding to the waste-gas opening, and it has struck in the meantime, intermediate the putting-in gear of the motor clutch 51 and the putting-out-of-gear of the motor clutch 52, with its upper arm against the fixed abutment 102 and by the clutch actuating-rod 43 disengaged the clutch 40 and engaged the clutch 41, thus preparing the waste-gas side on the left of the furnace for the reversal (Figs. 3 and 5). As shown in Fig 4, the whole mechanism of both furnace sides is perfectly symmetrical (see axis of symmetry A—A) and thus similarly operated on each furnace side in corresponding alteration, the proceeding in backward direction, e. g. in the direction: waste-gas to fresh-gas position, on the left-hand side being now described:

On the right-hand side, the analogous proceeding has been completed, and the runner 101 has returned to its end position to the left for waste-gas position of the right-hand side, the motor clutch 52 being again engaged by lever 53'. The runner 48 of the left-hand side is thus again on its travel to the left and has freed the lever 53, whereby the motor clutch 51 is automatically disengaged. The main control spindle 14 maintains still its highest position, the outlet cross-section is gradually narrowed more and more by the then occurring removal of the nozzle adjusting nuts 27, 28 from one another, and the sliding-nut 29 is being screwed upwards on the vertically fixed main control spindle 14. The left-hand clamping contrivance 92 is held in its disengaged position by the rope 91 attached to the clamping members 89 until the thrust-bearing disc 88 after engagement of the clamping members 89 has again been screwed up for a certain distance on the main control spindle 14 with the then existing rotary direction of the latter. As soon as, thus, the sliding-nut 29 has attained its highest position, it is automatically locked by the engagement of a suitable notch therein with the only tooth of the right-hand clamping contrivance 93, which is continuously kept in working position. As the clamping members 86 have firmly engaged the thrust-bear-

ing disc 88 after the levers 100 have been turned up, the thrust-bearing disc is screwed up whereupon also the left-hand clamping contrivance comes to action. The main control spindle begins to screw down within the guiding-nut 29 from its hitherto raised position, and the runner 48 comes into the path between the abutments 44, 45, of which the latter can again be turned manually to its working position. Fig. 10 shows how in conjunction with the disengagement and re-engagement of the abutment 45 the adjustment of the hereinafter shortly described correction apparatus to waste-gas and fresh-gas position respectively takes place by the common rod 124, the illustration showing at the left the fresh-gas position and at the right the waste gas position.

Hereinafter, the question of the limits of exactness is to be considered, within which the arrangement works during the whole adjustment to a fixed value of the working gas and during the sweeping of the bath surface. It may be assumed that the correct ratio of cross-sections exists for a fixed value with a burner adjustment to the nearest point of impact of the flame. With a change of the burner flap positions for displacing further the point of impact, the initially correct ratio of cross-section tests varies within certain limits. As the angles, for which the flaps oscillate, must normally remain constant for allowing a sweeping of the total bath surface in question at any gas value, said variation of the ratio of cross-sections is the larger, the smaller is the outlet cross-section in question at the nearest point of impact, or the higher is the value of the gas. Further regard must be paid to the difference in the specific weights of gas and air increasing more and more with increasing gas value.

Correction apparatus:

Said inexactnesses are dispensed with by the present invention in such a way that on the fresh-gas side the difference of the resulting energies of movement of gas and air does not exceed 15%, while on the waste-gas side the adjustment permits a difference of the heating temperatures of gas and air of less than 100° only. This is attained by a correction apparatus (Figs. 1 and 11) effecting on the fresh-gas side as well as on the waste-gas side a corresponding limitation of the widening of the outlet cross-section of the gas flue depending upon the gas value.

Hence it follows that a correction apparatus must be used, which is operated by the auxiliary control spindle 18, the driving of the sleeve 76 being effected by means of the toothed gearing 57, 181. In each end of said sleeve 76 a bolt 77, 78 is screwed and fitted each with a bounding arm 79 for the fresh-gas and 80 for the waste-gas adjust-

ment. The direction of the threads in the sleeve 76 or on the bolts 77, 78 is such that with the adjustment for a higher gas value the bolts are screwed out of the sleeve 76 and adapted, by the bounding arms 79 for fresh-gas supply and 80 for waste-gas withdrawal, to limit the widening of the gas flue outlet cross-section by the yieldingly arranged operating rods 9, 10 (Fig. 1) bearing upon the surfaces of the arms. As shown in Fig. 11 for one operating rod 10, the operating rods 9, 10 are each two-parted, one part 10 being arranged on the turning flap (4) and embracing the other part 10' that is linked to the main control spindle 14. A bolt 81' fixed on said latter part engages in borings of the other forked part 10 while a spring 82 encased at 81 allows a certain degree of movement between the two parts 10, 10'. The bounding arms 79 for fresh-gas supply and 80 for waste-gas withdrawal are arranged at an angle of 90° to one another. When reversing from fresh-gas to waste-gas position, and vice versa, each time the respective arms are turned into working position and held therein until the next reversion takes place. Fig. 10 shows that said reversal can be effected in a simple way, simultaneously with the manual turning-aside of the abutment 45, by means of the draw-bar 124'. To prevent collision between the operating rods 9, 10 and the bounding arms 79, the reversal must take place when the runner 48 lies at the abutment 44 (farthest point of impact of the flame). The whole arrangement works thus perfectly automatic, and that for both main operations: for the adjustment to a fixed value of the working gas and for the continuous sweeping of the whole bath surface, that is for a positive combustion directly on the bath surface. The control of the blowers for gas and air, of which the capacities must be varied corresponding to the quantity of gas and air to be supplied according to actual gas value, can be made dependent upon the runner 71 for indicating a certain gas value. The reversal of the arrangement at the change of direction of the furnace working takes place in a simple way by manually putting the abutment 45 into its disengaged or working positions. Furthermore, it must be noted that by a corresponding adjustment of the two abutments 44 and 45 on the gearing-rod 43 it is possible to dimension and to displace the area of impact on the bath level. An approachment of abutment 44 to the fixed abutment 45 displaces the area of impact toward the corresponding fresh-gas burner side, a uniform approachment of both abutments to one another continues the directly swept surface more to the middle part of the bath level, and so on. Finally, a mutual adjustment of the main operating elements, of

which the position is positively adjusted with reference to each other as it is mainly the question of screw-controlled movements, allows combinations which make the apparatus more than hitherto adapted for the various requirements of the furnace working.

What I claim is:

1. The method of working industrial gas furnaces having air and gas heating checker chambers, a bath receiving hearth and burners at opposite ends of the hearth, said method comprising preheating the streams of gas and air for combustion to an equal or predetermined different temperature for each thermal value of the gas, said preheating being done according to the principle that the greater the calorific value of the gas the smaller the amount of waste gas necessary for the preheating of the gas in relation to the amount of waste gas necessary for the preheating of air and vice versa, and adjusting the cross-section of the burner openings at the outlet end of the furnace so that the greater the calorific value of the gas the smaller the proportion, according to which the waste gases are distributed to the gas and air chambers.

2. The method of working industrial gas furnaces having air and gas heating checker chambers, a bath receiving hearth and burners at opposite ends of the hearth, said method comprising preheating the streams of gas and air for combustion to an equal or predetermined different temperature for each thermal value of the gas by an adjustment of the burner outlet flue cross-sections on the waste gas side and a consequent distribution of the waste gas quantities over the regenerative heating chambers, said preheating taking place according to the principle that the greater the calorific value of the gas and consequently the ratio of the amount of combustion air to the amount of heating gas, the greater must be the ratio of the air burner opening to the gas burner opening on the waste gas side and vice versa, and automatically adjusting the ratio of the burner outlet cross-sections on the fresh-gas side, said adjustment taking place according to the principle that in connection with the positive supply of the gas and air quantities the energies of movement of gas and air streams for each thermic value of the gas are to have such values that an intersection of the two streams takes place on the bath surface, the burner outlet flue axes being simultaneously and correspondingly adjusted and the whole combustion process taking place on the bath surface only.

3. The method of working industrial gas furnaces having air and gas heating checker chambers, a bath receiving hearth and burners at opposite ends of the hearth, said method comprising preheating the streams

of gas and air for combustion to an equal or predetermined different temperature for each thermal value of the gas by an adjustment of the burner outlet flue cross-sections on the waste gas side and a consequent distribution of the waste gas quantities over the regenerative heating chambers, the ratio of the burner outlet cross-sections on the fresh gas side being adjusted automatically in such a way that in connection with the positive supply of the gas and air quantities the energies of movement of gas and air streams for each thermic value of the gas have such a value that the intersection of the two streams takes place on the bath surface, the burner outlet flue axes being simultaneously and correspondingly adjusted, the whole combustion process thus taking place on the bath surface only and the inclination or direction of the burner outlet flue axes being changed in a continuous alteration, so that a to and fro travel of the point of the impact of the flame produced by the intersecting gas and air streams over the whole bath surface is obtained.

4. The method of working industrial gas furnaces having air and gas heating checker chambers, a bath receiving hearth and burners at opposite ends of the hearth, said method comprising preheating the streams of gas and air for combustion to an equal or predetermined different temperature for each thermal value of the gas by an adjustment of the burner outlet flue cross-sections on the waste gas side and a consequent distribution of the waste gas quantities over the regenerative heating chambers, the ratio of the burner outlet cross-sections on the fresh gas side being automatically adjusted so that with a positive supply of gas and air quantities the energies of movement of gas and air streams for each thermal value of the gas have such relative values that the intersection of the two streams takes place on the bath surface, the burner outlet flue axes being simultaneously and correspondingly adjusted, the whole combustion process thus taking place on the bath surface only, the inclination or direction of the burner outlet flue axes being changed in a continuous alteration, so that a to and fro travel of the point of impact of the flame produced by the intersecting gas and air streams over the whole bath surface is obtained and said change of the direction or inclination of the burner outlet flue axes being limited to a certain range or point of the bath surface.

5. The method of working industrial gas furnaces having air and gas heating checker chambers, a bath receiving hearth and burners at opposite ends of the hearth, said method comprising preheating the streams of gas and air for combustion to an equal or predetermined different temperature for

each thermal value of the gas by an adjustment of the burner outlet flue cross-sections on the waste gas side and a consequent distribution of the waste gas quantities over the regenerative heating chambers, the ratio of the burner outlet cross-sections on the fresh gas side being automatically adjusted so that in connection with a positive supply of gas and air quantities the energies of movement of gas and air streams for each thermic value of the gas have such relative values that the intersection of the two streams takes place on the bath surface, the burner outlet flue axes being simultaneously and correspondingly adjusted, the whole combustion process thus taking place on the bath surface only, the inclination or direction of the burner outlet flue axes being changed in a continuous alteration so that a to and fro travel of the point of impact of the flame produced by the intersecting gas and air streams over the whole bath surface is obtained, said change of the direction or inclination of the burner outlet flue axes being limited to a certain range point of the bath surface, the streams of gas and air receiving such energies of movement during the to and fro travel of the point of impact of the flame on the bath surface, which are required for a larger or smaller distance of said point of impact of the flame from the fresh gas burner, the burner outlet flue cross-sections being gradually narrowed or widened, and the ratio of the burner outlet cross-sections remaining constant during said adjustments provided a change of the last-mentioned ratio is not necessitated by a change of the calorific value of the gas.

6. A regenerative furnace having air and gas heating checker chambers, a bath receiving hearth, burners at opposite ends of the hearth and flaps in each burner outlet operable to regulate the cross-section thereof in accordance with the thermic value of the gas.

7. A regenerative furnace having air and gas heating checker chambers, a bath receiving hearth, burners at opposite ends of the hearth, flaps in each burner outlet operable to regulate the cross-section thereof in accordance with the thermic value of the gas, a main spindle controlling the positions of said flaps to effect the adjustment of the cross-section of said outlet and to effect further the shifting of the burner flue outlet axes owing to the necessary changes of the cross-sections during the to and fro travel of the flame and an auxiliary controlling spindle adapted to act upon said flaps to adapt the ratio of the burner outlet cross-sections to the instant calorific value of the gas.

8. A regenerative furnace having air and gas heating checker chambers, a bath receiv-

ing hearth, burners at opposite ends of the hearth, flaps in each burner outlet operable to regulate the cross-section thereof in accordance with the thermic value of the gas, a main spindle controlling the positions of said flaps to effect the adjustment of the cross-section of said outlet and to effect further the shifting of the burner flue outlet axes owing to the necessary changes of the cross-sections during the to and fro travel of the flame, an auxiliary controlling spindle adapted to act upon said flaps to adapt the ratio of the burner outlet cross-sections to the instant calorific value of the gas and a gearing for controlling said spindles whereby the various adjustments and a reversing of said burners from their fresh gas position to the waste gas position are automatically effected.

In testimony whereof I have hereunto set my hand.

WALTHER SCHUCANY.
